AIR CONDITIONER CASING

Philip S. Egan, Evanston, Ill., assignor to Sears, Roebuck and Co., Chicago, Ill., a corporation of New York

Application April 8, 1953, Serial No. 24,408

Term of patent 3½ years

(Cl. D62—4)

To all whom it may concern:

Be it known that I, Philip S. Egan, a citizen of the United States and a resident of Evanston, Illinois, in the county of Cook and State of Illinois, have invented a new, original, and ornamental Design for an Air Conditioner Casing, of which the following is a specification, reference being had to the accompanying drawing, forming a part hereof.

Fig. 1 is a perspective view of an air conditioner casing embodying my new design; and

Fig. 2 is a fragmentary perspective view of the same with the hinged panel thereof in open position.

The other side panel is substantially similar to the side panel seen in Fig. 1.

The back and bottom are plain.

I claim:

The ornamental design for an air conditioner casing, as shown and described.

PHILIP S. EGAN.
